Attorney, Agent, or Firm—Buchanan Ingersoll; Robert J. Pugh

[57] **CLAIM**

The ornamental design for a shin protective pad, as shown and described.

DESCRIPTION

FIG. 1 is a front elevational view of a shin protective pad showing our new design;

FIG. 2 is a rear elevational view thereof; and,

FIG. 3 is a left side elevational view thereof. The broken lines in all views represent conventional stitching.

FIG. 1

FIG. 2

FIG. 3
